2 Sheets-Sheet 1

UNITED STATES PATENT OFFICE.

JEFFERSON C. CARNER, OF MARIETTA, OHIO.

BY-PASS.

Application filed August 11, 1923. Serial No. 656,981.

To all whom it may concern:

Be it known that I, JEFFERSON C. CARNER, a citizen of the United States, residing at Marietta, in the county of Washington 5 and State of Ohio, have invented a new and useful By-Pass, of which the following is a specification.

This invention relates to a by-pass barrel, one of its objects being to provide a structure 10 of this character which, when the well tubing is pulled before the fluid has been returned to the well, will allow the fluid to flow downwardly to the producing strata, the agitation of fluid thus set up serving to 15 clean the structure from paraffin deposits, thereby causing an increase in the flow of the fluid.

A further object is to provide a by-pass 20 barrel which, by allowing the fluid to flow downwardly during the pulling of the tubing, saves the waste that would otherwise occur when the tubing is pulled, it being estimated that without such a means for permitting down flow of the fluid, approximately six barrels of oil would be wasted on the derrick floor every time fifteen hundred feet 25 of two inch tubing was pulled.

A further object is to provide a structure 30 of this character which can be attached to the bottom of the regular working barrel of any pumping oil well without interfering with the operation of the same.

With the foregoing and other objects in view which will appear as the description 35 proceeds, the invention resides in the combination and arrangement of parts and in the details of construction hereinafter described, it being understood that changes in the precise embodiment of the invention 40 herein disclosed may be made within the scope of what is claimed without departing from the spirit of the invention.

In the accompanying drawings the preferred form of the invention has been shown.

45 In said drawings—

Figure 1 is a section through a portion of the regular working barrel of a well and the working valve, a portion of the trip plunger being shown.

50 Fig. 2 is a section through that portion of the structure below the part illustrated in Fig. 1 and illustrating the lower portion of the trip plunger, the standing valve, the agitating tube, and other parts associated there-

with, the valves in both Figs. 1 and 2 being shifted to permit down flow of fluid.

Fig. 3 is a section on line 3—3, Fig. 1.

Fig. 4 is a view of the structure shown in Fig. 1 and showing the valves in their normal or cut off positions.

Fig. 5 is a sectional view of that portion of the structure located below the portion illustrated in Fig. 4.

Referring to the figures by characters of reference 1 designates the regular working barrel of a well, the lower end of which is coupled, by a sleeve 2, to the upper end of the casing 4 of the working valve. A tube 5 is supported within the casing 4 and is provided, near the upper and lower ends 60 of said casing, with ports 6 and 7 respectively opening into the casing 4. The usual working valve 8 is mounted for reciprocation within the tube 5 and has a tubular core 9 on which are mounted the usual conical washers 10 and cups 11 of leather or the like. A cage 12 is formed at the upper portion of the working valve and houses a ball valve 13. Extending upwardly from the end of the working valve is a threaded 70 stud 14 adapted to be engaged by the rod 15. Longitudinal grooves 16 are formed in the outer surface of the cage and open through the top thereof.

A trip plunger 17 is secured to and extends 75 downwardly from the working barrel and is adapted to move upwardly and downwardly within said barrel and relative to the tube 5.

The lower portion of the casing 4 is coupled by a sleeve 18 to the upper portion of a casing 19, and secured in the upper end of this casing 19 and extending downwardly into the lower end portion thereof is a tube 20 having upper and lower ports 21 85 and 22 respectively opening into the casing 19.

A screw plug 23 is located close to and above the port 22 and constitutes an abutment for one end of a coiled spring 24 the other end of which bears against a standing 100 valve 25 mounted for reciprocation in the tube 20 and having a cage 26 at its upper end. A guide tube 27 is secured to the upper end portion of the standing valve and extends downwardly through the spring 105 24 and plug 23 and projects below the tube 20, the lower end of this tube 27 being open as shown. A ball valve 28 is loosely mount-

ed in the cage and is normally seated on the upper end of the tube 27. The longitudinal grooves in the outer face of the cage 26 and which have been indicated at 29 open upwardly through the top of the cage, said top being tapered as shown at 30 so as to be normally seated against a rib 31 arranged within the upper portion of the tube 20. This normal position of the cage against its seat has been illustrated in Fig. 4. The standing valve includes the usual arrangement of conical washers 32 and cupped washers 33 designed to work in tube 20.

The lower end of the casing 19 is coupled by a sleeve 34 to a perforated tube 35 that hangs downwardly within the well and constitutes an agitating tube.

Under normal conditions the spring 24 holds the tapered upper end of the cage 26 against the seat 31. The well can be pumped in the usual manner and it is obvious that the improvements constituting the present invention will not interfere with the working thereof. When it is desired to draw the tubing without wasting the oil contained therein, the rod 15 is moved downwardly so as to bring the working valve to the position shown in Fig. 1. Thus the ports 6 will be placed in communication with the grooves 16 and all fluid contained within the barrel will be free to flow downwardly through port 6 and into casing 4 and thence downwardly through the ports 7. When the working valve is lowered, as described, the trip plunger 17 will come against and force downwardly the standing valve so as to bring the grooves 29 into communication with the ports 21. Thus the oil passing downwardly from the ports 7 will be free to flow into the casing 19 and thence downwardly through ports 22 into the tube 35. It will here flow outwardly through the apertures in tube 35 in jets that thoroughly agitate the contents of the producing strata and dislodge accumulations of paraffin or the like. Consequently when the well is again used for the purpose of elevating oil or the like, it will be found that the fluid will flow more freely than would otherwise be possible. Thus the invention constitutes a means not only for effecting a saving of oil contained within the working barrels and tubing, but also a means for removing paraffin adhesions from the walls of the producing strata.

During the ordinary working of the apparatus the cups 11 and 33 of the valve are protected by the tubes 5 and 20 from the rush of fluid passing through the apparatus.

For the purpose of insuring proper ejection of the jets of fluid through the apertured tube 35, a plug 36 is seated in the lower end of said tube 35 where the tube is coupled, by a sleeve 37, to a lower tube section 38.

What is claimed is:—

1. The combination with a working barrel, a casing coupled thereto, a lower casing; an apertured agitating tube closed at its lower end, and means for coupling the upper end of the agitating tube to the lower casing, of tubes supported longitudinally within the casing, a working valve mounted for reciprocation within the tube in the upper casing, there being upper and lower ports within said tube, a rod connected to the working valve, said valve when in raised position constituting means for closing communication between the barrel and the upper ports in the tube, a yieldingly supported standing valve in the tube in the lower casing, said tube having upper and lower ports, the upper ports being normally closed by the standing valve, and means operated by the downward movement of the working valve for engaging and lowering the standing valve to open communication through the ports for gravitation through the casing to the agitating tube of fluid supported within the barrel. 90

2. The combination with a working barrel, of superposed connected casings coupled to the barrel, an apertured agitating tube connected to and depending from the lower casing and closed at its lower end, alining tubes within the upper and lower casings and extending longitudinally thereof, a working valve mounted for reciprocation within the upper tube, said tube having upper and lower ports, the upper ports being closed by the working valve when said valve is in raised position, a rod for actuating the working valve, a yieldingly supported standing valve within the tube of the lower casing, there being upper and lower ports in said tube, the upper ports being normally closed by the standing valve, said standing valve including a cage at its upper end, a tube extending from the cage and downwardly through and beyond the valve, and a check valve within the cage, and means carried by the working valve, for engaging the standing valve to shift it against the action of its yielding means to establish communication through the ports between the working barrel and the agitating tubes. 105

3. The combination with an apertured agitating tube closed at its lower end, a working barrel, and upper and lower communicating casings connecting the barrel to the agitating tube, of tubes within the upper and lower casings, each of said tubes having upper and lower ports, a working valve mounted for reciprocation within the upper tube, a rod connected thereto, said working valve being shiftable to open or close the upper ports in the upper tube, a spring supported standing valve within the lower tube and normally closing the upper ports in said tube, said standing valve having a tube ex- 110 120 125 130

- tending longitudinally therein and open at its lower end, and a check valve normally closing the upper end of the tube, and a trip plunger carried by the working valve 5 and movable against the standing valve to shift it downwardly and open communication between the barrel and the agitating tube for gravitation of liquid contained within the barrel.
- 10 4. The combination with a working barrel, and an apertured agitating tube closed at its lower end, of communicating casings constituting a connection between the working barrel and the agitating tube, a working 15 valve mounted for reciprocation in the barrel, and means controlled by the downward movement of the working valve for delivering to the agitating tube by gravity fluid contained within the working barrel.
- 20 5. The combination with a working barrel, an apertured agitating tube, and upper and lower casings constituting a connection between the barrel and the tube, of upper and lower tubes supported within the respective 25 casings and having ports therein, a working valve movably mounted within the upper tube and the working barrel, and means within the lower tube and controlled by the movement of the working valve in one direction, for releasing fluid supported within the working barrel for gravitation to the agitating tube.
6. The combination with a working valve, of means for delivering fluid therefrom in jets against the walls of the producing strata 35 of a well, said means including a perforated agitating tube closed at its lower end, connected upper and lower casings constituting a connection between the barrel and the upper end of the agitating tube, tubes supported within the respective casings and each having upper and lower ports, a working valve mounted for reciprocation within the upper tube for controlling the flow of fluid through the ports in said tube, a standing valve yieldingly supported within the lower tube and normally closing the upper ports therein, and means operated by the movement of the working valve in one direction for shifting the standing valve and for setting up communication through the ports between the barrel and the agitating tube. 40
- 45 In testimony that I claim the foregoing as my own, I have hereto affixed my signature in the presence of two witnesses.

JEFFERSON C. CARNER.
